BOWLING BALLS HAVING PERMANENT IDENTIFICATION INDICIA

Samuel J. Giangreco, Kansas City, Mo.

Application December 16, 1957, Serial No. 703,151

2 Claims. (Cl. 40—2.2)

This invention relates to bowling equipment and more particularly to bowling balls having owner identification indicia thereon.

It is, of course, known that bowling balls have been marked in various ways in the past to indicate the owner of the ball, the registration number of the same and/or the particular manufacturer of the article, but the most widely used of the past methods, consisting of cutting shallow, V-shaped grooves in the outer surface of the ball and then painting these grooves with white pigmented material, has not been satisfactory because the white paint readily wears away during use of the ball, thereby making the grooves barely discernible. Prior attempts to solve this problem have not met with success at a reasonable price, and especially after production and sale of the ball.

It is, therefore, the object of this invention to provide a bowling ball having permanent identification indicia which overcome the above defined problems and disadvantages and which will not become dislodged nor wear away during use of the ball.

In the drawing:

Figure 1 is an elevational view of a bowling ball having permanent identification indicia in the outer surface thereof;

Fig. 2 is a fragmentary, cross-sectional view taken substantially on the line 2—2 of Fig. 1 and illustrating the way in which channels are formed in the ball in a way to receive polymerizable material which subsequently presents a tough, relatively elastic, crack resistant solid adapted to withstand shock incident to use of the ball;

Fig. 3 is a fragmentary, cross-sectional view similar to Fig. 2 and illustrating a modified form of the invention wherein imaginary planes parallel to opposed walls forming the channels converge adjacent the center of the ball;

Fig. 4 is a fragmentary, enlarged, cross-sectional view similar to Fig. 3 and showing a third modification of the present invention wherein the channels are configured in a novel manner to anchor the indicia material into the outermost surface of the bowling ball; and

Fig. 5 is a fragmentary, enlarged, cross-sectional view on the same line as Fig. 4 and illustrating still another form of indicia channel construction serving to anchor the polymerized material in the outer surface of the ball.

Briefly, the present invention contemplates forming a series of channels in the outermost surface of a bowling ball and corresponding to specified identification indicia, and subsequently introducing liquid or paste material into the channels and which is capable of undergoing polymerization therein to a tough, relatively elastic, crack resistant solid adapted to withstand shock incident to use of the ball so that the indicia will not become dislodged nor wear away during such use of the ball. The invention further contemplates applying a portion of the polymerizable material to the surfaces of the channels presenting the indicia to thereby soften or otherwise act on the material from which the ball is constructed to the extent that, upon

2

polymerization of the material within the indicia channels, the resulting solid is firmly bonded to the ball.

Referring to the drawing, it can be seen that the bowling ball designated 10 and provided with conventional finger 5 and thumb openings 12 is suitably grooved with a milling machine or the like to present a series of channels 14 corresponding to the desired indicia. For example, if it is desired to mark ball 10 with a person's name, it is merely necessary to groove the outer surface of ball 10 to a predetermined depth with channels corresponding to the desired name. It is to be pointed out that channels 14 may be most conveniently formed by utilization of a vertical mill controlled by parallel arms, in turn connected to a suitable, vertically disposed member which 15 may be traced over a name template. The depth of the channels 14 will depend upon various factors including the width of the groove being cut, as well as the complexity of the design being inscribed on the outer surface of ball 10. Manifestly, suitable provision may be made 20 on the milling machine for varying the depth of channels 14 as desired.

In the form of the invention illustrated in Figs. 1 and 2, channels 14 are grooved with a standard vertical milling machine so that opposed walls 16 and 18 of each of the 25 channels 14 are transversely parallel, and it is also to be noted that the distance between the bottom 20 of each of the channels and the outermost surface 22 of ball 10 is somewhat greater than the transverse width of channels 14 between opposed walls 16 and 18.

Subsequently, channels 14 are filled with a liquid or 30 paste-like material capable of polymerizing within the grooves to a solid state, thereby presenting identification indicia 24. Although various materials may be utilized to form indicia 24, the preferred formulation has been 35 found to include an admixture of methyl methacrylate and polymethyl methacrylate combined with a suitable promoter capable of causing the acrylates to copolymerize within channels 14 at room temperature. In this respect, it is pointed out that the exact materials utilized 40 as well as the proportions thereof will vary with the materials employed, but utilizing the preferred materials outlined above it has been determined that an admixture of three parts by weight of polymethyl methacrylate and one part by weight of methyl methacrylate monomer with 45 a sufficient quantity of a promoter to cause the material to copolymerize at room temperature will give the desired results. Many promoting agents can be utilized to cause the methyl methacrylate and polymethyl methacrylate to 50 polymerize at room temperature and especially useful are the amine promoters which coact with suitable curing agents which oxidize in the presence of the amines. For example, one satisfactory promoter has been found to be suitable quantities of an admixture of benzoyl peroxide and dimethyl-p-toluidine.

Inasmuch as channels 14 are formed with a milling machine or similar apparatus, it can be appreciated that the surfaces of walls 16 and 18 and bottom 20 are relatively rough and somewhat porous as contrasted with the outer surface 22 of ball 10 which has been polished. 55 Therefore, in the preferred process, the liquid or paste admixture of polymerizable material is introduced directly into the channels 14 and because of the rough or porous nature of walls 16 and 18 and bottom 20, the material penetrates into and fills all of the tiny pores and holes in the surfaces of walls 16 and 18 and bottom 20. A strong mechanical bond is thereby formed between indicia 24 and ball 10 upon polymerization of the material. It is also believed that a chemical bond is 60 formed between indicia 24 and ball 10 because of the fact that certain of the substances in the initial admixture of the polymerizable material are capable of acting on or softening the substances from which ball 10 is con- 65 70

structed. It is of course well known that bowling balls are fabricated with various rubber-like materials such as the lignites or "Plioform," produced by the Goodyear Tire & Rubber Company, Akron, Ohio, and, inasmuch as these rubber-like materials are softened to a certain extent by the monomeric material, upon polymerization of the methyl methacrylate and the polymethyl methacrylate, a strong bond is formed between ball 10 and solid indicia 24.

In order to absolutely assure that solid indicia 24 are securely bonded to ball 10, it has been found that by applying or coating the surfaces of walls 16 and 18 and bottom 20 of channels 14 with a quantity of the liquid monomeric material, and in particular the methyl methacrylate monomer, prior to introduction of the admixture thereto, the liquid material tends to soften or break down the substance from which bowling ball 10 is constructed so that, upon copolymerization of the methyl methacrylate and the polymethyl methacrylate to form solid 24, the latter is firmly bonded to the surfaces of walls 16 and 18 and bottom 20.

Various pigments may be incorporated into the polymerizable material prior to introduction of the same into channels 14 to thereby make indicia 24 a different color than the outermost surface 22 of ball 10, and in this respect, any type of color may be produced which will suitably contrast with the color of ball 10. Inasmuch as most bowling balls 10 are black or a similar dark color, utilization of a pigment in the polymerizable material is not ordinarily necessary because methyl methacrylate and polymethyl methacrylate, for example, polymerize to a relatively white solid state so that the necessary contrast between indicia 24 and the outermost surface 22 of ball 10 is obtained.

A slight excess of the liquid polymerizable material is introduced into channels 14 so that the material extends slightly above the outermost surface 22 of ball 10, and then a suitable pressure plate having a face conforming to the outermost configuration of outer surface 22 of ball 10 is placed in position over the filled channels 14 and pressure is applied to ball 10 until polymerization of the synthetic resin material is completed. This pressure prevents the formation of voids in the polymerizable material during the time the same is undergoing solidification and also assures that solid indicia 24 is firmly bonded to all of the surfaces of walls 16 and 18 and bottom 20.

After complete polymerization of the liquid material, the pressure plate is removed and the outermost portions of solid indicia 24 filed down until the same are level with outer surface 22 of ball 10.

A slightly modified form of the invention is illustrated in Fig. 3, wherein it can be seen that bowling ball 110 is grooved with a suitable milling machine to present channels 114 corresponding to the desired identification indicia, and it is to be noted that channels 114 are exactly similar to channels 14 with the exception that while walls 116 and 118 of channels 114 are transversely parallel, planes through walls 116 and 118 pass through

substantially the center of ball 110 so that each of the indicia 124 are located substantially on corresponding radii of ball 110. The indicia 124 are formed in a manner similar to the method described above and the only change effected is the manner of grooving ball 110 to present channels 114. It has been determined that disposition of channels 114 in radial positions further prevents solid indicia 124 from being dislodged from ball 110 during use of the latter.

The channels receiving the identification indicia may be formed in various other ways as illustrated in Fig. 4, wherein it can be seen that channels 214 formed in the outermost surface 222 of ball 210 are grooved in a manner so that the transverse distance between walls 216 and 218 adjacent outer surface 222 of ball 210 is substantially less than the transverse width of channels 214 adjacent bottom 220 thereof. In this manner, solid indicia 224 are firmly anchored in channels 214 and indicia 224 will not become dislodged from ball 210 by virtue of shock imparted to the latter during use.

Still another manner of anchoring the indicia in the outermost surface of a bowling ball is shown in Fig. 5 wherein it can be seen that the channels 314 milled in the outer surface 322 of ball 310 are configured in a manner so that the walls 316 and 318 are substantially parallel along the major portion thereof and adjacent outer surface 322 but which converge outwardly as bottom 320 is approached, so that the channels 314 are substantially transversely wider adjacent bottom 320 than at the outer surface 322 of ball 310.

It is now manifest that various modifications may be made in the instant invention without departing from the spirit thereof, and it is therefore intended to be limited only by the scope of the appended claims.

Having thus described the invention what is claimed as new and desired to be secured by Letters Patent is:

1. An article of manufacture comprising a bowling ball having an outer, rubber-like, hard cover portion provided with a series of channels in the outer face thereof corresponding to identification indicia each defined by a pair of side walls and a bottom having relatively initially rough surfaces; and a filler of tough, relatively elastic, crack-resistant, polymerized, synthetic resin material completely filling said channels and capable of withstanding shock incident to use of the ball, said material being physically and chemically bonded directly to the surfaces defining said channels.

2. An article of manufacture as set forth in claim 1 wherein said material is polymethyl methacrylate.
